UNITED STATES PATENT OFFICE.

WILLIAM B. BRADSBY, OF GREENVILLE, ILLINOIS, ASSIGNOR OF ONE-HALF
TO CHARLES STEWART, OF SAME PLACE.

THILL-COUPING.

SPECIFICATION forming part of Letters Patent No. 402,502, dated April 30, 1889.

Application filed February 28, 1889. Serial No. 301,486. (No model.)

To all whom it may concern:

Be it known that I, WILLIAM B. BRADSBY, a citizen of the United States, residing at Greenville, in the county of Bond and State of Illinois, have invented new and useful Improvements in Thill-Couplings, of which the following is a specification.

My invention relates to improvements in thill-couplings; and it consists in certain novel features, hereinafter described and claimed.

In the accompanying drawings, Figure 1 is a perspective view of a thill-coupling embodying my invention. Fig. 2 is a plan view, showing the nut or sliding collar in horizontal section. Fig. 3 is a vertical longitudinal section of the coupling. Fig. 4 is a view showing a modified form of locking-spring.

My improved thill-coupling is applied to the front axle, A, and is secured thereto by the clip B in the usual manner, as shown. The body C of the coupling is formed by extending the clip-plate mounted on the ends of the clip B forward beyond the axle and bifurcating the front end of the said extended portion, as shown at D. The body C is further provided in its sides with longitudinal recesses E, in which I pivot the coupling arms or latches F. The said coupling-arms are pivoted at or near their rear ends, and their outer surfaces are inclined outward and forward, as shown most clearly in Fig. 2, and they are provided at their front ends with the inwardly-projecting pivot-pins G, which are adapted to engage the eye of the thill-iron H, as will be readily understood.

The forward portion of the clip-plate is exteriorly threaded, as shown at I, and on this threaded portion I mount a sliding nut or collar, J, which is adapted to bear upon the outer inclined surfaces of the coupling-arms and is provided in its outer edge with a series of longitudinal notches, K, as shown. By moving this collar in or out the coupling-arms will be caused to move toward or away from each other at their front ends, as will be readily understood, and in order that the said nut or collar may not be moved too far backward, and also to provide for disengaging the coupling-arms from the thill-irons, the rear ends of the said coupling-arms are provided with the out-

wardly-projecting points or shoulders L, against which the nut will contact when moved inward, so as to throw the front ends of the said arms apart. The collar or nut is held against undue rotation by means of a spring, M, which has one end secured in the front end of the body and extends rearwardly substantially parallel with the side of the body and has its rear end engaging a perforation in the rear end of one of the coupling-arms, its intermediate portion engaging one of the notches of the said collar or nut.

The body C is provided in its upper and lower sides with the longitudinal recesses P, in which I place the ends of the anti-rattling spring Q, the central portion of which passes vertically across the end of the body C and bears upon the end of the thill-iron, so as to press it toward the pivot-pins G at the ends of the coupling-arms and thereby prevent its moving thereon, as will be readily understood.

In practice the locking-spring M is disengaged from the nut or collar J, and the said nut or collar is then moved inward, so as to throw the front or outer ends of the coupling-arms apart. The thill-iron is then inserted between the branches of the bifurcation in the body C, and the nut or collar then moved forward so as to press the front ends of the coupling-arms together and force the pivot-pins G of said arms into engagement with the eye of the thill-iron. The locking-spring is then engaged in one of the notches of the collar and the coupling will be completed.

From the foregoing description it will be seen that I have provided a very simple and efficient thill-coupling in which all the parts are compactly arranged and by means of which the thills will be securely attached to the axle and will be prevented from rattling.

The locking-spring can be easily disengaged when it is desired to release the thills, as it is necessary only to turn the nut or collar slightly forward to release the rear end of the spring, when its resilience will at once disengage it from the collar or nut. After the nut has been adjusted to the proper point the spring is again secured in place and the nut will be held against movement.

The anti-rattling spring in my device can

be given more or less tension and thereby caused to exert a greater or less pressure on the thill by turning the nut outward or inward, as will be readily understood. When the nut is turned outward, the ends of the spring will be pressed together, so that its central portion will be pressed outward to bear against the thill.

In Fig. 4 I have shown a locking-spring which is secured at one end, *a*, on the upper side of the body and extends laterally beyond the side of the body and is coiled, as at *b*, and thence extends forward parallel with the side of the body and engages one of the notches in the nut. The front end of the spring is bent inward and passed around a stud, *O*, on the upper side of one of the coupling-arms. It is obvious that the use of this spring involves no departure from my invention.

Having thus described my invention, what I claim, and desire to secure by Letters Patent, is—

1. A thill-coupling comprising the body, the coupling-arms pivoted thereto and having inwardly-projecting pivot-pins at their front ends adapted to engage the eye of the thill-iron, and the sliding collar acting on the said arms to force them into engagement with the eye of the thill-iron, as set forth.
2. The combination of the body, the coupling-arms pivoted thereto and adapted to en-

gage the eye of the thill-iron, the collar mounted on the body and acting on the coupling-arms to force them into engagement with the eye of the thill-iron, and the locking-spring secured on the body and engaging the said collar, as set forth.

3. The combination of the body, the coupling-arms pivoted thereto and having inclined outer surfaces and provided at their front ends with inwardly-projecting pivot-pins adapted to engage the eye of the thill-irons, the collar mounted on the body and acting on the inclined surfaces of the coupling-arms and provided in its outer side with a series of longitudinal notches, and a locking-spring secured to the body and engaging one of the notches of the collar, as set forth.

4. The combination of the body, the coupling-arms pivoted thereto, the anti-rattling spring fitted on the body and passing vertically across the end of the same, the collar mounted on the body and acting on the coupling-arms, and the locking-spring secured on the body and engaging the collar, as set forth.

In testimony that I claim the foregoing as my own I have hereto affixed my signature in presence of two witnesses.

WILLIAM B. BRADSBY.
